SHAVING KIT

Henry W. Bauder, El Paso, Tex., assignor of one-third to Oren Stigler and one-third to C. E. Joseph, both of El Paso County, Tex.

Application December 22, 1947, Serial No. 793,168

1 Claim. (Cl. 132—81)

1

One of the prime objects of the invention is to design a fountain shaving kit, including a hollow handle in which shaving cream is contained, and provide means for extruding predetermined quantities thereof into the brush as desired.

Another object is to provide a shaving kit including a plunger formed with a floating washer for accurately and closely engaging the side walls of the container, thus eliminating any leakage of the shaving cream back of the plunger as the mechanism is actuated.

A further object is to design a shaving kit including means to prevent saturating and soaking of the brush bristles with the cream during the period the brush is not in use.

Still a further object of the invention is to design a shaving kit including a cap for housing and shielding the brush bristles, which cap forms a handle for a conventional razor, so that the brush, shaving cream and razor are incorporated in a single, compact kit or item.

A further object of the invention is to provide a simplified shaving kit composed of few parts, all of substantial design and construction, which can be readily and economically manufactured and assembled, and which can be easily and quickly cleaned and loaded.

Still a further object is to design a compact, neat-appearing shaving kit which can be readily packed in a traveling bag or case, and which is especially adaptable for travelers, soldiers, sailors and others where limited packing space is available, and where it is desired to have all shaving material, etc. in a single kit.

To the accomplishment of the foregoing and related ends, said invention then consists of the means hereinafter fully described, and more particularly pointed out in the claim, the annexed drawings and following description setting forth in detail, certain means and one mode of carrying out the invention, such disclosed means and mode illustrating, however, but one of the various ways in which the principle of the invention may be used.

In the drawings:

Fig. 1 is a side-elevational view of my new shaving kit.

Fig. 2 is a vertical, sectional view thereof.

Fig. 3 is an end-elevational view showing the razor attachment.

Fig. 4 is a fragmentary, side-elevational view showing the end of the container, the razor and the guard.

Fig. 5 is a transverse-sectional view taken on the line 5—5 of Fig. 2.

2

Fig. 6 is also a transverse-sectional view taken on the line 6—6 of Fig. 2.

Fig. 7 is a transverse-sectional view taken on the line 7—7 of Fig. 2.

Fig. 8 is an isometric view of the razor guard. Referring now more specifically to the drawings in which I have shown the preferred embodiment of my invention. There is provided a hollow handle member 10 which can be constructed or molded of plastic or any other desired material, the one end being open as shown and being internally threaded as at 11 to accommodate the threaded end of the plug member 12, which member is centrally bored as at 13 to accommodate a centrally disposed section 14 of a cap member 15, said cap in turn being bored as at 16 to accommodate the one end of a threaded stem 17, which is securely and non-rotatably mounted therein.

A washer member 18 is mounted on the stem 17 as shown, and a special nut 19 is threaded on the stem 17 and bears against said washer to hold it tightly against plug 12 and the centrally disposed section 14 of the cap 15.

The opposite end of the handle is shouldered as at 20, and is threaded as shown for threaded engagement with the open threaded end 21 of the bristle cap 22, this end of the handle being centrally bored and threaded as at 23, and accommodates a preferably metallic bristle holder 24, the lower end of which is threaded for engagement with the threaded section 24 of the handle, said bristle holder comprising inner and outer cylindrical sections 25 and 26 respectively, to form a concentric bristle holder, the inner end wall 27 of which is inwardly dished or conical-shaped as shown to form a holder for the bristles B, and protects the inner ends of the bristles from shaving cream S.

The shaving cream S is placed in the hollow portion 27 of the handle 10, the section immediately adjacent the bristle holder being shouldered and angled as at 28 to register with and lead to the cream passage P which opens into the center of the bristle body, and I wish to direct particular attention to the fact that the inner wall of the end section of the handle is also conical shaped as at 28 to eliminate any shoulders or pockets in which shaving cream might lodge and dry.

A shank 30 is mounted on the free end of the bristle cap 22, and a conventional razor structure R is mounted thereon in the usual manner, a blade guard 31 being provided and slidably engages the edges of the razor structure and is formed with a stop 32 to limit the sliding movement of the guard.

A plunger 33 is mounted on the stem 17, and is formed with a centrally disposed, threaded opening 34, and spaced-apart concentric flanges 35 are formed integral with said plunger, a resilient washer 36 being mounted between said flanges and is formed with an enlarged center opening 37 so that the washer is free to float with relation to said flanges, permitting it to remain accurately centered at all times, regardless of the I. D. of the washer, this washer being of a diameter to form a tight fit with the wall of the container, preventing rotation thereof as the stem is actuated.

Metallic bands 38 and 39 are provided on the handle, and the upper end of the bristle cap is also preferably formed of metal, these bands being mounted directly adjacent the open ends of the container and cap to eliminate cracking or breaking of the material of which the shell is formed, and further serving to ornament the kit.

To load the container, the plug and cap 12 and 15 are first unscrewed from the handle 18 so that the stem and plunger can be withdrawn as a unit, the cap being first rotated to bring the plunger 33 tightly against the nut 19. The container is then filled with shaving cream S, after which the cap and plug are again screwed in position, and rotation of the cap 15 forces the plunger 33 downwardly in the shell, squeezing the cream through the passage 25 and into the bristles B. The ends of the bristles are then dipped into water, and upon application to the face, a rich lather is quickly produced.

After the shaving is completed, the razor is cleaned, the guard 31 is again applied and the cap 22 is then placed over the bristles and screwed to position. Small openings 42 are provided in the bristle cap for drying and ventilation purposes.

The device forms a complete kit; it provides everything necessary for shaving; it is neat, compact, and of pleasing appearance; and the entire structure can be easily and economically manufactured and assembled.

From the foregoing description, it will be obvious that I have designed and perfected a simple, practical, inexpensive, and compact shaving kit which is convenient to use, which can be easily cleaned, assembled, and in which any parts can be replaced when broken or worn.

What I claim is:

A brush comprising a hollow handle having an open internally threaded end, a bristle container 10 mounted in said threaded end, and provided with a conical-shaped, dished head open to said hollow handle, bristles in said bristle container, a centrally disposed passage in the container and open to said handle and the bristles respectively, 15 a plug threaded in the opposite end of the hollow handle and formed with a centrally disposed opening, a cap revolvably mounted in the opening in said plug, a threaded spindle anchored in said cap, a washer on the spindle and engageable with the plug and cap respectively, a nut on the spindle for securing the cap in assembled relation, a piston adjustably mounted on said spindle and including spaced-apart flanges, a resilient washer member mounted between said flanges and movable transversely between said flanges to form 20 and maintain a relatively tight, leak-proof engagement with the side walls of said container for forcing the shaving cream downwardly into the bristles as the cap is rotated.
